PROCESS FOR CONVERTING HYDRO-CARBON MATERIAL

Raymond C. Lassiat, Swarthmore, Pa., assignor to Houdry Process Corporation, Wilmington, Del., a corporation of Delaware

Application December 19, 1947, Serial No. 792,724

5 Claims. (Cl. 196—52)

1

My invention relates to a process of converting hydrocarbon material.

For reasons known in the art and as referred to generally in pending application Serial No. 766,714, filed August 6, 1947, now Patent No. 2,548,912, it is desirable, in the art of converting hydrocarbons, for liquid phase hydrocarbon material to be applied directly to hot contact material as it gravitates through a reaction housing. This is true particularly when the charging stock contains heavy fractions because the latter, in the presence of the gravitating contact material, are either vaporized and converted, or converted directly to lower boiling products.

In the process and apparatus herein disclosed, contact material, in bed formation, gravitates through a housing and, in known manner, forms the conversion or reaction zone proper. Above this bed, in accordance with my invention, contact material having suitable conversion temperature gravitates in layer formation along a downwardly inclined path offering the sole resistance to downward movement of the contact material during passage thereof throughout the length of said path and, as this operation proceeds, atomized hydrocarbon material is directed into engagement with said gravitating layer of contact material. Preferably, the aforesaid downwardly inclined path is defined by the interior surface of an inverted conical member around which the layer of contact material extends in a circumferentially complete manner and, below which, the contact material falls freely into engagement with the upper bed surface.

In a more restricted sense, the inverted conical member is disposed in vertically aligned relation beneath an upright conical member, these members being suitably spaced from the interior housing surface and arranged in chamber-forming relation so that a suitable atomizer may be supported within the chamber. During operation, the contact material gravitates first along the surface of the upright conical member and then along the interior surface of the inverted conical member, these members, due to their inclination, offering slight frictional resistance to downward movement of the contact material and this, in accordance with the invention, is the sole effect restricting such downward movement.

Various other objects and advantages of my invention will become apparent from the following detailed description.

My invention resides in the process of converting hydrocarbon material, the process steps and

2

features of the character hereinafter described and claimed.

For an understanding of my invention and for an illustration of one form of apparatus with which the invention may be practiced, reference is to be had to the accompanying drawings, in which:

Fig. 1 is a vertical sectional view, partly in elevation, showing a conversion housing and associated mechanism as constructed in accordance with one form of my invention;

Fig. 2 is a horizontal sectional view, partly in inverted plan, taken on the line 2—2 of Fig. 1 looking in the direction of the arrows;

Fig. 3 is an enlarged vertical sectional view, partly in elevation, showing an atomizer; and

Fig. 4 is a horizontal sectional view, partly in plan, taken on the line 4—4 of Fig. 3 looking in the direction of the arrows.

Referring particularly to Fig. 1, I have shown a vertical housing 1 which, in horizontal cross section, may be circular or of any other suitable configuration. The housing 1 defines a reaction zone wherein hydrocarbon material is cracked or otherwise converted in the presence of contact material C which moves downwardly therethrough under the influence of gravity, the contact material C, usually after regeneration thereof in a suitable regenerating zone, not shown, being introduced into said housing 1 in suitable manner, as by an inlet pipe 2 extending through the top housing wall at the center thereof.

In the form of the invention herein shown, although not necessarily, a shallow receptacle-like member 3 is suitably supported in the upper portion of the housing 1, said member 3 having a central discharge pipe 4 opening therethrough and extending downwardly therefrom. Slidably associated with the discharge pipe 4 is a horizontal valve member 5 having an operating handle extending through and terminating exteriorly of the housing 1. The valve member 5 comprises a passage 5a the diameter of which is suitably less than said internal diameter of the pipe 4. Below the member 3, a horizontal frame 6 may be suitably secured to the interior surfaces of the housing 1, said frame 6 having an upright (non-inverted) conical member 7 welded or otherwise suitably secured thereto.

In accordance with the invention, a suitable downwardly inclined, path-defining member such as a frusto-conical member 8 is disposed below the conical member 7, said member 8 being supported in any suitable manner, as by a horizontal frame 9 which may be secured thereto and to in-

terior surfaces of the housing 1 by welded joints or equivalent. The member 8 comprises a lower discharge passage 8a and the upper end thereof may comprise a tubular portion 8b which extends upwardly around the lower portion of the conical member 7. The tubular portion 8b has interior diameter somewhat greater than the exterior diameter of the lower surface of the conical member 7 and, by reason of the fact that said conical member 7 and the tubular portion 8b are symmetrically related to each other, there is an annular slot or passage 10 therebetween having uniform width throughout the circular length thereof. As shown, the respective longitudinal axes of the pipe 4, the conical member 7, and the conical member 8 together with its discharge passage 8a and tubular portion 8b are in coincidence and these axes coincide, preferably, with the longitudinal axis of the housing 1.

In operation, regenerated or other heated contact material C having suitable conversion temperature passes continuously from the pipe 2 and, to suitable extent, fills the receptacle 3 which defines an upper zone of the housing 1. When the valve member 5 is positioned as illustrated, namely, with its passage 5a alined with the pipe 4, a desired control is effected on the amount of contact material which gravitates downwardly through the discharge pipe 4 from the receptacle 3. The valve member 5, then, restricts the downward flow of contact material under the influence of gravity through that part of said pipe 4 above the plane of said valve member 5. After leaving the valve member 5, the contact material engages and is deflected outwardly by the conical member 7, the contact material thereafter passing through the annular passage 10 and then engaging and being deflected inwardly by the conical member 8 as a layer L of contact material whereupon, as a generally tubular freely falling stream S, it passes through the discharge passage 8a of said last named member 8. The width of the annular passage 10 is such that the surfaces defining said passage offer no restriction to movement of contact material downwardly therethrough. Therefore, as the contact material travels below the plane of the valve member 5, it falls freely under the influence of gravity except for the frictional effect developed by the conical members 7 and 8 and, on the respective exterior and interior surfaces of these members, the contact material forms the described layer or stream L which is circumferentially complete around the periphery thereof, Fig. 2. In connection with the foregoing, the tubular portion 8b of the member 8 is provided so as to restrain undesired bouncing movement of the contact material.

After leaving the aforesaid discharge passage 8a, the contact material falls freely under the influence of gravity generally in tubular fashion until it comes to rest upon and at least partly defines the upper surface of a bed B of gravitating contact material which constitutes the reaction zone proper, the bottom surface of this bed of contact material engaging a tube sheet 11 horizontally disposed in the housing 1 and suitably secured to the interior surface thereof.

If desired, a plurality of pipes 12 may be spaced uniformly around the interior surface of the housing 1. The upper ends of these pipes 12 communicate with the chamber defined by the member 3, which may support said pipes, and the lower ends thereof terminate at the upper surface of the aforesaid bed of contact material.

They are adapted to be traversed by a portion, preferably a minor portion, as 20% more or less, of the total amount of contact material gravitating downwardly through the housing 1. The pipes 12, when utilized, contribute as regards maintenance of the surface of the bed B at a level approximately that of the lower ends of said pipes.

The aforesaid tube sheet 11 supports a plurality of suitably spaced depending pipes 13 which open therethrough. The contact material passes through these pipes 13 and thereafter, in known manner, may be discharged from the housing 1 for passage through a conduit 14 which should contain a valve 15 utilizable for controlling the flow of contact material therethrough so that the contact material forming the bed B is restricted or impeded as it moves downwardly through the housing 1 in solid bed fashion under the influence of gravity.

Adjacent the lower end of the housing 1, any suitable arrangement may be provided for disengaging cracked or converted vapors from the contact material C. To this end, as diagrammatically indicated, the aforesaid tube sheet 11 may support a plurality of tubes 16 which upstand therefrom and open therethrough, the tubes 16 supporting a plurality of suitably arranged channel members 17, or equivalent, which are disposed in inverted relation so that, in known manner, they may be utilized for disengagement of vapors from the contact material, the vapors thereafter entering the tubes 16 by way of passages 16a formed, respectively, therein. A pipe 18 opens through the wall of the housing 1 below the tube sheet 11 and communicates with the space above the adjacent conical piles of contact material. This pipe 18 may have associated therewith a control valve 19 and it is adapted to receive and conduct the converted vapors to any suitable destination.

In accordance with the invention, the contact material, as it gravitates along the interior surface of the conical member 8, is engaged by atomized liquid hydrocarbon material to be cracked or otherwise converted. To this end, an atomizer A is suitably located within the chamber defined by the members 7 and 8 preferably in alinement with the longitudinal axis of the housing 1 and it may be supported in any suitable manner, for example, by a pipe 20 extending from the exterior of the housing 1 to the interior thereof. The atomizer A should be one which produces fog, mist, spray or other liquid particles having suitable dimensions from the liquid hydrocarbon material admitted thereto and it may be of any suitable character. Preferably, although not necessarily, it is of the general character disclosed in the pending application of James E. Evans, Serial No. 756,032, filed June 20, 1947.

In the form of the invention hereinafter specifically described, hydrocarbon material which is substantially or totally in the liquid phase is admitted to the atomizer A and, hence, it should be adapted for efficient atomization of material of this character as referred to in the aforesaid pending application Serial No. 756,032 and as illustrated on the drawings of this application. Thus, as shown, said atomizer A comprises a casing 21 having a top wall 22 through which the lower end of the aforesaid pipe 20 opens and to which said pipe is secured. The casing 21 has a lower wall 23 above which said casing 21 comprises vertical and horizontal circular plate portions 21a and 21b related to each other in

right angle relation. In the form of atomizer herein shown, although not necessarily, a row of ports or passages 21c open through the respective casing portions 21a and 21b, these ports 21c being alined in sets. Hydrocarbon material admitted by the pipe 20 to the casing 21 passes to and through each of said ports 21c.

In view of the foregoing, it clearly appears that the conical members 1 and 8 together with the atomizer A are located in a chamber D of the housing 1, said chamber D being bounded, at its lower end, by the zone defined by the upper surface of the bed B and, at its upper end, by the aforesaid zone defined by the receptacle 3.

When hydrocarbon material is to be cracked in the housing 1, the contact material C hereinbefore referred to should be catalytic in character and the temperature thereof, upon admission to the housing 1, should range between 800° F. and 1000° F. or higher for example, about 900° F. Any suitable kind of catalytic contact material may thus be utilized such, for example, as activated clay pellets, or synthetic silica-alumina pellets or beads, etc. having suitable major dimensions such as between $\frac{1}{8}$ and $\frac{3}{4}$ of an inch. Other suitable catalysts for cracking include synthetic plural oxide composites, silicious or non-silicious in character and containing for example, zirconia, alumina or beryllia. In lieu of a cracking operation, other types of conversion operations such, for example, as one wherein hydrocarbon material of the character referred to below is desulphurized under known conditions with catalytic contact material of the general character referred to above, or equivalent. Or, reforming or dehydrogenation of naphthas or other normally liquid hydrocarbons may be effected in the presence of the above or other desired types of catalyst, certain of which are well known in the art. In lieu of the conversion operations described above, heavy hydrocarbon material may be vaporized and viscosity-broken in the presence of inert contact material of known character.

During operation with suitable cracking contact material, vapors such, for example, as vaporized gas oil, naphtha or lighter hydrocarbons having suitable elevated temperatures, as in a range from 850° F. to 950° F., are admitted continuously to the housing 1 by way of a conduit 24 which should open thereinto at a higher level than the aforesaid pipe 20. Simultaneously, liquid hydrocarbon material such, for example, as a suitable residual stock, topped or reduced crude having temperature elevated into a suitable range as, for example, from 400° F. to 800° F. is charged continuously through the pipe 20 under superatmospheric pressure ranging, for example, from 10 lbs. to 200 lbs. per square inch gauge or as otherwise may be required for causing the atomized liquid material from the atomizer A to engage and properly penetrate the layer L of contact material gravitating along the interior surface of the conical member 8. The liquid hydrocarbon material thus traversing the pipe 20 passes through the atomizer casing 21 and the alined atomizer ports 21c of the respective sets thereof are traversed, respectively, by streams of liquid hydrocarbon material. The streams of liquid material from each pair of said ports 21c engage each other in head-on relation with resultant production of atomized liquid material which, as a mist or fog, moves downwardly in inclined relation and, as a circumferen-

tially complete stream, Fig. 2, engages the contact material last named.

The base diameter of the conical member 1 and the corresponding major dimension of the conical member 8 may be such as is suitable and desirable. Preferably, however, these dimensions are substantial, for example, approximately one-half the internal diameter of the housing 1 and, if so, it follows that the aforesaid gravitating layer L of contact material is relatively thin. By reason of this condition and further by reason of the fact that downward movement of the contact material is restricted only in the manner described above, it follows that the atomized liquid material is effectively distributed in a uniform manner on the individual pieces of contact material. This, of course, is highly desirable because promoting the efficiency of the cracking operation.

The contact material, after movement thereof through the discharge passage 8a, falls freely under the influence of gravity generally as the described tubular stream S. Further, during downward movement of the contact material along the interior surface of the conical member 8, the thickness of the layer L increases in a progressive manner until, at the discharge passage 8a, said layer L has maximum thickness. Accordingly, it follows that the thickness of the tubular stream S of contact material is substantially the same as that of the aforesaid layer L at the lower end thereof. The foregoing is in accordance with a detailed feature of the invention. Thus, during operation of the atomizer A as described above, some of the atomized liquid material, instead of being applied directly to the contact material forming the layer L, migrates downwardly and is intercepted by the contact material forming the tubular stream S. In addition, atomized liquid material which tends to migrate upwardly through the annular passage 10 is intercepted by the contact material passing through this passage.

Accordingly, in view of the foregoing, it follows that, within the chamber defined by the conical member 8, atomized liquid material is applied in an effective manner to the gravitating contact material. Further, with the disclosed system, migration of atomized liquid material into engagement with the interior surface of the housing 1 and the pipes 12 is largely or substantially prevented. Should this happen to any substantial extent, there is resultant formation of adherent deposits of carbonaceous material which, in the course of time, separate into chunks that move into and through the bed B with resultant partial or complete plugging of the outlets at the bottom of the housing 1. This, of course, is undesirable and is substantially prevented, in accordance with my invention, as described above.

As stated, hydrocarbon vapors, which in connection with a cracking operation preferably have temperature substantially higher than that of the liquid hydrocarbon material admitted to atomizer A, are admitted to the housing 1 by way of the pipe 24. These vapors pass through the housing 1, concurrently as regards the contact material C, and in the presence thereof are converted to cracked products. In so doing, the heat content of these vapors, by reason of the temperature relation referred to immediately above, assists as regards vaporization of the liquid hydrocarbon material entering said housing 1 through the atomizer A and provide a desired

control on the relative quantities of contact material and hydrocarbon material traversing the housing 1. Simultaneously, in the manner described above, atomized liquid hydrocarbon material is engaged with the layer L of contact material with resultant vaporization of such atomized liquid material and formation of cracked products while passing through the housing 1 concurrently as regards the contact material C. As regards the total charge entering the housing 1, the ratio of vapors to liquid material may be such as is suitable and desirable. Thus, for example, between 10% and 30% of the charge may be in the liquid phase for passage to the atomizer A and the remainder in the vapor phase for passage through the pipes 24.

Accordingly, in view of the foregoing, it will be understood that hydrocarbon material admitted to the housing 1 by way of the pipes 23 and 24 is converted in the presence of the contact material C to produce cracked products. As the operation proceeds, hydrocarbon vapors, principally, fill the aforesaid chamber D under pressure determined by the pressure existing in the hereinbefore described pipe 18. In known manner, a suitable sealing medium such as a stream of flue gases, is admitted to the top of the housing by way of a pipe 1a, Fig. 1, this sealing medium being maintained under pressure slightly greater than that of said hydrocarbon vapors last named in order to prevent passage of these hydrocarbon vapors upwardly through the pipe 2. Due to this pressure relation which exists in the chamber D, the hydrocarbon material admitted thereto as described above, is caused to pass downwardly concurrently as regards the gravitating contact material, this hydrocarbon material being cracked in the presence of said contact material and the resulting cracked vapors being disengaged therefrom at the channel members 17. Thereafter, in the form of the invention herein shown, these cracked vapors enter the tubes 16 by way of the respective passages 16a, pass downwardly through said tubes and enter the space below the tube sheet 11, said cracked vapors passing to any suitable destination by way of the hereinbefore described pipe 18. In known manner and by suitable means, not shown, a suitable gaseous medium, such as steam is admitted to the lower portion of the housing 1, below the pipe 18 and under pressure above that existing at the level thereof, to prevent passage of hydrocarbon vapors through the pipe 14.

As the operation proceeds, the spent contact material C passes through pipes 13 and then leaves the housing 1 by way of the pipe 14. Thereafter, in suitable manner, said spent contact material is regenerated and then returned to the inlet pipe 2 for readmission to the housing 1.

In the form of the invention hereinbefore specifically described, the hydrocarbon material admitted to the atomizer A was stated to be substantially or totally in the liquid phase. However, the invention is not to be thus limited. If desired, mixed phase hydrocarbon material (which may be formed from liquid phase and vapor phase material of the same character and proportioned as described above) may be admitted to the atomizer A and, if so, the atomizer should be adapted for efficient atomization of such mixed phase material as described in the aforesaid pending application Serial No. 756,032. When mixed phase material is thus supplied to

the atomizer A, the quantity of vapors traversing the pipe 24 may be substantially decreased or entirely eliminated.

Obviously many modifications and variations of the invention as hereinbefore set forth may be made without departing from the spirit and scope thereof and, therefore, only such limitations should be imposed as are indicated in the appended claims.

10 1 claim as my invention:

1. In a hydrocarbon conversion process where-
in liquid hydrocarbons contact moving particles
of hot contact material in a conversion zone
under heat exchange conditions such that said
15 liquid hydrocarbons are at least partially
vaporized, the steps which comprise feeding a
stream of said contact material to the upper portion
20 of a smooth, downwardly converging frusto-
conical impenetrable surface, gravitating said
contact material over said surface as a circum-
ferentially complete thin layer of particles, uni-
formly distributing atomized liquid hydrocarbons
25 on the particles in said layer from an upwardly
enclosed location, and flowing said particles
downwardly below said frusto-conical surface as
a freely falling stream.

2. In a hydrocarbon conversion process where-
in liquid hydrocarbons contact moving particles
30 of hot contact material in a conversion zone un-
der heat exchange conditions such that said
liquid hydrocarbons are at least partially
vaporized, the steps which comprise flowing
35 downwardly a stream of said contact material
divergently outward from its vertical axis so as
to form a circumferentially complete stream
which increases in diameter as it moves unob-
structedly downward, flowing said contact mate-
40 rial downwardly as a freely falling annular
stream to the upper portion of a smooth, down-
wardly converging frusto-conical impenetrable
surface, gravitating said contact material over
45 said surface as a circumferentially complete thin
layer of particles, uniformly distributing atomized
liquid hydrocarbons on the particles in said layer
from an upwardly enclosed location below the
diverging stream of contact material, and flowing
50 said particles downwardly below said frusto-coni-
cal surface as a freely falling stream.

3. In a hydrocarbon conversion process where-
55 in liquid hydrocarbons contact moving particles
of hot contact material in a conversion zone un-
der heat exchange conditions such that said
liquid hydrocarbons are at least partially
vaporized, the steps which comprise introducing
55 a downwardly moving compact column of said
contact material into said conversion zone, dis-
charging contact material from the bottom of said
column as a freely falling stream, deflecting said
stream outwardly from the vertical axis thereof
60 by a downwardly diverging impenetrable surface,
discharging said contact material from said down-
wardly diverging surface as a freely falling an-
nular stream onto the upper portion of a smooth,
65 downwardly converging frusto-conical impene-
trable surface, gravitating said contact material
over said downwardly converging surface as a
circumferentially complete thin layer of particles,
flowing atomized liquid hydrocarbons onto the
70 particles in said layer from a location below said
downwardly diverging impenetrable surface, and
flowing said particles downwardly below said
frusto-conical surface as a freely falling stream
onto the surface of a bed of said contact ma-
terial.

75 4. In a hydrocarbon conversion process where-

in liquid hydrocarbons contact moving particles of hot contact material in a conversion zone under heat exchange conditions such that said liquid hydrocarbons are at least partially vaporized, the steps which comprise feeding a stream of said contact material to the upper portion of a smooth, downwardly converging frusto-conical impenetrable surface, gravitating said contact material over said surface as a circumferentially complete thin layer of particles, directing atomized liquid hydrocarbons at least partially to said layer of particles, intercepting atomized liquid hydrocarbon material that has not contacted said layer with a freely falling circumferentially complete stream of contact material discharged from the lowermost portion of said frusto-conical surface and accumulating the contact material discharged from said surface on the top of a downwardly moving non-turbulent bed of contact material in the lower part of said conversion zone.

5. In a hydrocarbon conversion process where-in liquid hydrocarbons contact moving particles of hot contact material under heat exchange conditions such that said liquid hydrocarbons are at least partially vaporized, the steps which comprise gravitating a circumferentially complete

5
10

15

converging stream of contact material downwardly in a contacting zone laterally bounded by an impenetrable surface over which said stream moves, introducing liquid hydrocarbons to a central location in a region contiguous to said stream, said region being upwardly bounded by an impenetrable surface and laterally by a circumferentially complete stream of contact material, flowing atomized liquid hydrocarbons generally laterally from said location so as to engage said stream of contact material, and flowing contact material after said engagement with liquid hydrocarbons downwardly as a freely falling circumferentially complete stream.
